(57) **CLAIM**

The ornamental design for a nail strap, as shown and described.

DESCRIPTION

FIG. 1 is a perspective view of the preferred nail strap design.

FIG. 2 is a first side elevation view of the preferred nail strap design.

FIG. 3 is a front elevation view of the preferred nail strap design.

FIG. 4 is a second side elevation view of the preferred nail strap design.

FIG. 5 is a back elevation view of the preferred nail strap design.

FIG. 6 is a top plan view of the preferred nail strap design; and,

FIG. 7 is a bottom plan view of the preferred nail strap design.

The broken line showing of the upper portion of the nail strap is for illustrative purposes only and forms no part of the claimed design.
